UNITED STATES PATENT OFFICE.

HENRY VOGT AND ROBERT H. BURNS, OF BROOKLYN, NEW YORK.

STEAM-BOILER.

SPECIFICATION forming part of Letters Patent No. 449,922, dated April 7, 1891.

Application filed August 18, 1890. Serial No. 362,278. (No model.)

To all whom it may concern:

Be it known that we, HENRY VOGT and ROBERT H. BURNS, citizens of the United States, and residing in Brooklyn, Kings county, and 5 State of New York, have invented certain new and useful Improvements in Steam-Boilers, of which the following is a specification, reference being had to the accompanying drawing.

Our improvements relate specially to the 10 construction of a vertical boiler in such manner that an efficient combustion of the coal and the gases arising therefrom, as well as an efficient circulation of the water of the boiler, shall be effected.

15 Our improvements consist in the construction, arrangement, and combination of the several parts or portions comprising the boiler, as hereinafter described and specified.

In the accompanying drawing is presented 20 a vertical sectional view of a boiler embodying our improvements.

The letter A designates the furnace-chamber of the boiler, and B the line of grates of said furnace.

25 D designates the furnace-door.

C designates a special combustion-chamber set above the furnace-chamber and connected with said furnace-chamber by means of a collection of draft-tubes E.

30 F designates a collection of draft-tubes furnishing heating-surface to the upper water-chamber of the boiler.

G designates a special water-circulation tube or tubes passing through combustion-chamber C and connecting the water-chamber about tubes E with the water-chamber about tubes F.

H designates a brace-rod tying the crown-sheet of the furnace-chamber to the tube-sheet 40 forming top of boiler.

I designates the shell of the boiler.

L designates a special fire-brick or heat-holding lining for combustion-chamber C to assist and improve the operation of the combustion 45 of the gases. Brace-rod H passes through central water-tube G, connecting upper and lower water-spaces together.

The letter T designates a series of air tubes or ducts adapted to act as braces to the sides 50 of the furnace-chamber A and combustion-chamber C, as well as to furnish a new sup-

ply of air to the said chambers, according as it is needed to effect perfect combustion.

In the operation of this boiler the gases arising from the coal pass through tubes E 55 and enter the combustion-chamber C, where they spread and additional combustion takes place, the unconsumed gases of the furnace being delayed here, owing to the enlarged space volume of chamber C. Should there 60 not be a sufficient quantity of air pass through the grate and furnace to effect a perfect combustion, the air-tubes T permit of the entrance of a controlled quantity of fresh air to the furnace and to the combustion-chamber C. 65 These tubes T are plugged or kept open, according as more or less fresh air is required to effect the combustion of the coal-gases. After the gases have been properly consumed the draft moves the heat up through tubes 70 F, where it is taken up by the surrounding water and steam, passing out at the top to the chimney in the usual manner.

To control the temperature of the chamber C, it may be lined with fire-brick or heat-retaining material L, which will give out heat 75 when required to the gases within.

The sides of both furnace and combustion chambers are tapered to assist in the reliable circulation of the water in the boiler and to 80 relieve the central portion of the boiler and tube sheets. A circulation is effected up through the central tube or tubes G to the upper water-chamber also. Any number of brace-rods H can be used, it only being necessary to have a water-tube G for each to pass through, the said water-tubes doing two duties, allowing water circulation and the passing through of the brace-rods.

What we claim as new, and desire to secure 90 by Letters Patent, is—

1. In a vertical steam-boiler, in combination with the furnace-chamber, a special combustion-chamber set above said furnace-chamber, a collection of draft-tubes connecting the two 95 said chambers together, one or more central water-tubes connecting the upper and lower water-spaces together, and a collection of draft-tubes furnishing heating-surface to the upper water-space of the boiler, substantially 100 as set forth.

2. In a vertical steam boiler, in combination

with the furnace-chamber, a special combustion-chamber set above said furnace, a collection of draft-tubes connecting the two said chambers together, a collection of air-tubes 5 connecting the said special combustion-chamber with the outside of boiler, one or more central water-tubes connecting the upper and lower water-spaces together, and a collection of draft-tubes furnishing heating-surface to 10 the upper water-space of the boiler, substantially as set forth.

3. In a vertical steam-boiler, in combination with the furnace-chamber, a special combustion-chamber set above said furnace-chamber, 15 a collection of draft-tubes connecting the two said chambers together, one or more central water-tubes connecting the upper and lower water-spaces together, a collection of air-tubes connecting both the special combustion-chamber and the furnace-chamber with the outside 20 of boiler, and a collection of draft-tubes fur-

nishing heating-surface to the upper water-space of the boiler, substantially as and for the purposes set forth.

4. In a vertical steam-boiler, in combination 25 with the furnace-chamber, a special combustion-chamber set above the furnace-chamber, a collection of draft-tubes connecting the two said chambers together, a central water-tube connecting the upper and lower water-spaces 30 of the boiler together, a brace-rod passing through said central water-tube and tying the furnace-chamber crown-sheet to the tube-sheet forming the top of boiler, and a collection of draft-tubes furnishing heating-surface 35 to the upper water-space of the boiler, substantially as and for the purposes set forth.

HENRY VOGT.
ROBERT H. BURNS.
